UNITED STATES PATENT OFFICE

JOHN EDGAR HIRES, OF ARDMORE, PENNSYLVANIA, ASSIGNOR TO SCOTT PAPER COMPANY, A CORPORATION OF PENNSYLVANIA

PAPER ROLL

Application filed December 6, 1929. Serial No. 412,142.

My invention relates to that class of toilet paper roll in which the central core of the roll is formed integral with the continuous web wound about the core, whereby the core and roll is formed from a continuous length of paper and at a single operation.

In carrying out my invention, I wind the advancing end of a paper web between rolls having corrugated peripheries and, at the same time, apply glue or paste to the paper web so that the same is wound upon a corrugated mandrel and pressed into a multi-ply corrugated core upon which the web may be continuously wound but without the application of glue, with the result that a finished toilet roll package may be produced with a corrugated core.

In the manufacture of paper of this character, the wide web may be slit into a plurality of narrower webs and these narrower webs simultaneously wound upon the same mandrel in producing the finished roll with the corrugated core.

A roll of paper formed in this manner may provide a continuous unperforated web structure or it may be perforated at intervals along its length to permit it to be readily divided into sheets, similarly to the manner in which ordinary toilet paper rolls are formed.

My improvements in respect to apparatus may be employed in an ordinary slitting and perforating machine of any suitable character adapted to feed the slitted webs to the corrugated winding mandrel and pasting and forming devices, such as hereinafter described.

My invention also consists of the completed toilet roll package having the corrugated core of special construction described hereinafter and more particularly defined in the claim.

My invention will be better understood by reference to the drawing, in which: Fig. 1 is an end view of a toilet roll paper package embodying my improvements; Fig. 2, is a side view of the same; Fig. 3 is a side view illustrating the winding mandrel, glue applying means, and squeeze or press roll; and Fig. 4 is a diagrammatic representa-

tion of a slitting and perforating machine to which my improvements are applied.

The paper roll shown in Fig. 1 comprises a corrugated core 2 of multi-ply construction and produced by winding a pasted web upon itself while supported upon a corrugated mandrel and pressing the pasted web into corrugated relation by a squeeze roll 4 shown in Fig. 2. The corrugated multiple ply core is thus of a more or less dense glued construction which, while having reasonable pliability, retains its shape and thus provides a core member within the body of the completed roll. When the corrugated core is released from pressure of the squeeze roll and the application of glue, the further rotation of the mandrel will cause the flat web of paper to be wound cylindrically about and upon the corrugated core and as a continuation thereof, as shown at 3 and as will be understood by reference to Fig. 1. The diameter and length of the roll may be varied to suit the requirements of the manufacturer.

In the commercial manufacture of rolls of the character herein set out, I may slit and transversely perforate a web of paper in a machine of well known construction and provide the same with suitable corrugated mandrels, a pressure or squeeze roll cooperating with the mandrels, and a glue applying mechanism movable into or out of gluing position with respect to the mandrel which may be in action in forming the corrugated core, all of which will be understood by reference to Figs. 3 and 4. Such machines comprise a roll supporting frame 5 from which the web is delivered to transverse perforating apparatus 6 comprising a cylinder 7 about which the paper web is guided by guide rolls 8 and 9 and upon which the web is perforated by perforating cutters 10, the same being operated in the usual manner. After the paper web has been perforated transversely at intervals along its length, the web is slit longitudinally into narrower webs of commercial size by the slitting cutters 11. The plurality of perforated webs thus provided are guided over a roller 12 and are then received upon the core mandrel 13 and the paper brought into contact with a glue apply-

ing roller 14 journaled in and receiving glue from a reservoir 15. The glue reservoir 15 is suitably guided at 16 so that it may be brought into and out of contact with the paper on the mandrel 13 and may be shifted into and out of cooperation with said mandrel by a suitable lever 17 which may be manually operated or otherwise, as preferred.

The glue applying roll 14 is preferably made of corrugated form so as to cooperate with the mandrel roll 13, and while the said glue applying roll will not only apply the glue but will also tend to corrugate the core being formed upon the mandrel, I prefer to employ an additional corrugated roll 4 arranged above the mandrel 13 and having weight sufficient to insure the corrugation and press the paper into the glued recesses to densify the multiple-ply core during its formation. The corrugating or press roll 4 may be journaled in a hinged frame 18 which will insure proper presentation of the press roll 4 to the mandrel 13, or permit it to be turned up out of the way after the core has been formed and during the winding of the cylindrical web 3 about the core.

For convenience, it is customary to provide a pivoted mandrel frame 19 in which a plurality of the mandrels 13 may be journaled, so that said mandrels may be successively brought into operative relation with the glue applying roll and press roll. The mandrel may be driven in the usual manner by a friction drive (not shown) which will permit compensation for the different diameters of the roll being wound. The general character of a slitting and roll winding machine suitable for use in connection with my improved mandrel and corrugated core making devices may be found in Patent No. 999,375, dated August 1, 1911, and also No. 886,332, dated April 28, 1908, and reference is made thereto by way of explanation of details which it is not thought necessary to illustrate in the present application.

When the multi-ply core has been completed by the cooperation of the mandrel 13, glue applying roller 14, and press roll 4, the said glue applying roll and press roll are moved out of contact with the mandrel or core and thereafter the roll is completed by the uncorrugated portion of the web as at 3 in Fig. 1. When the proper diameter of roll 5 is formed the mandrel carrying frame 19 is shifted to bring a new mandrel into operative relation with the web and, at the same time, to move the completed roll to the rear as shown in Fig. 4. Thereupon the glue applying roll 14 and the press roll 4 is returned to cooperative relation with the new mandrel and the paper web is ruptured at the point 20 between the new mandrel and the finished roll. Thereupon the free end of the web is wound upon the new mandrel for the making

of a core as hereinbefore described. The former mandrel with its finished rolls is removed from the adjustable frame 19 and the rolls stripped from the mandrel.

A roll having a corrugated core of the character herein described is more properly supported in cylindrical shape than where the core is formed of cylindrical shape. Furthermore, less material is required in forming the multi-ply core than would be required with the cylindrical core, because the cell-like formation between the core and the cylindrical portion of the roll gives a bracing effect with a lesser quantity of paper web than would be required in a cylindrical core of the same strength. Furthermore, the corrugated form of the core gives a certain amount of elasticity or yieldingness at its points of internal contact than when threaded upon a cylindrical support and, moreover, may be rotatable upon said support but normally positioned thereon without objectionable looseness. It will be understood that this elasticity of the core may be utilized to impart a reasonable drag thereon when withdrawing the web of paper therefrom, so that there will be no unnecessary tendency to spin and objectionably unwinding the roll.

No claim is made in this application to the means or apparatus employed in the manufacture of the improved paper roll, the same constituting a separate invention which will be the subject matter of another application.

I have described my improved article and the means for making same in that particularity which I deem to be the best exposition of my invention and that which I prefer in commercial practice, but I do not restrict or confine myself to the minor or secondary details, as such are susceptible of modification, which may be resorted to as matters of mechanical skill and without a departure from the spirit of the invention.

I claim:

An improved roll of paper in web form which consists of a core of corrugated cross section comprised of a plurality of convolutions of a continuous web of paper firmly glued together into a yielding multiply structure of corrugated form and about which the continuous web of paper is wound in separable cylindrical convolutions, said core integral with the cylindrical convolutions and providing cellular spaces about the axis thereof and between it and the cylindrical convolutions of said web of paper.

In testimony of which invention, I hereunto set my hand.

JOHN EDGAR HIRES.
